UNITED STATES PATENT OFFICE.

WILLIAM J. SCOTT, OF BOSTON, MASSACHUSETTS.

DESIGN FOR AN AMBULANCE-BODY.

SPECIFICATION forming part of Design No. 23,614, dated August 28, 1894.

Application filed June 8, 1894. Serial No. 514,266. Term of patent 7 years.

To all whom it may concern:

Be it known that I, WILLIAM J. SCOTT, residing in Boston, in the county of Suffolk and State of Massachusetts, have invented and 5 produced a new and original Design for an Ambulance-Body, of which the following description, in connection with the accompanying drawing, is a specification, like letters on the drawing representing like parts.

10 This design relates to an ambulance wagon and consists in an ambulance body distinguished by its peculiar shape, which will be hereinafter set forth and claimed.

The drawing shows in side elevation the 15 body of an ambulance wagon embodying this design.

The leading feature of my design consists in a long body portion *a* upwardly and downwardly inclined at its front end to form a cut 20 under *a'* and provided with the curved foot board *a²* extended from the downwardly inclined side of the cut under *a'*, the latter forming the seat *b*. The body portion *a* is made oblong in shape and at the rear of the 25 seat, the said body extends a much greater distance than in ambulance wagons as now

commonly constructed, so that the appearance of the ambulance is marked by the abnormally long body at the rear of the seat and the short foot board in front of the said 30 seat.

The body *a* is provided with a covered top *b'* having its sides flush or substantially flush with the sides of the said body, and the straight sides of the top *b'* are provided with 35 windows *b²* and with an opening *b³* made in the sides above the said windows and provided with shutters *b⁴* shown in their open position, and by means of which ventilation is effected.

The top *b'* is provided with side curtains *d* and with the rear curtain *d'*.

I claim—

The design for an ambulance body herein shown and described.

In testimony whereof I have signed my name to this specification in the presence of 45 two subscribing witnesses.

WILLIAM J. SCOTT.

Witnesses:

JAS. H. CHURCHILL,
J. MURPHY.
